UNITED STATES PATENT OFFICE.

JAMES H. ROSENTHAL, OF LONDON, ENGLAND, ASSIGNOR TO THE BABCOCK & WILCOX COMPANY, OF NEW YORK, N. Y.

AUTOMATIC FEED-WATER REGULATOR.

SPECIFICATION forming part of Letters Patent No. 723,313, dated March 24, 1903.

Application filed March 6, 1902. Serial No. 96,943. (No model.)

To all whom it may concern:

Be it known that I, JAMES H. ROSENTHAL, a subject of the King of Great Britain, residing at Oriel House, Farringdon street, London, England, have invented certain new and useful Improvements in Automatic Feed-Water Regulators for Steam-Generators, of which the following is a specification, reference being had therein to the accompanying drawings.

10 This invention has for its object to provide improved apparatus for controlling the admission of feed-water to steam-boilers or like vessels, so as to automatically maintain an approximately uniform water-level, the height 15 of which may, however, be varied.

The invention is illustrated in the accompanying drawings, in which—

Figure 1 is a horizontal section, and Fig. 2 a cross-section, of the improved feed-regulator as fitted to the shell or drum of a boiler. Fig. 3 shows a sectional end elevation of a modification in which the float-lever of the regulator is balanced.

As shown by the drawings, the improved apparatus comprises a casing A, secured by an open flange connection A' to the boiler-drum B, the casing being formed with an inlet branch A², through which the feed-water enters, and an outlet branch A³, through which 30 and the feed-check valve the water is delivered to the boiler. Within the casing is secured a liner C, having in it diagonal or inclined ports c', opening, preferably, to the inlet branch A², and within the liner is fitted a hollow cylindrical valve D, having in it corresponding ports d². The cylindrical valve D has attached to it a lever E, extending into the boiler and terminating in a float F, which by the rise and fall of the water-level turns 40 the valve D on its axis within the liner, and the ports d² in it, which are shown in the mean position in line with or open to the ports c' in the liner, are more or less opened or closed by this partial rotation of the valve. The 45 valve D is also adapted to slide endwise within the liner, and for this purpose a screw-spindle G is provided and passes through a stuffing-box H in the casing-cover and a nut in the bridge I, a hand-wheel J being fixed 50 on its outer end. The inner end of the spin-

dle terminates in a disk G', which turns in ball or other antifriction bearings K between a cross-web of the valve D and an end cap or cover D'. By means of the screw-spindle the valve D may be traversed, so that the effective area of opening of the diagonal ports c' and d² may be varied, while the arrangement of ball-bearings between the regulating-spindle and the valve permits of the latter turning freely on its axis, the packed gland 60 around the spindle not interfering with its action, so that friction is reduced to a minimum. For the purpose of balancing the valve D an orifice D³ may be formed in the cross-web of the valve, or the valve may be otherwise balanced.

In the modification shown at Fig. 3 the weight of the float is balanced by a counter-weighted lever L, connected to the float-lever E; but in other respects the apparatus is identical with that shown at Figs. 1 and 2.

In the drawings, the valve D is shown in its middle position corresponding to the mean water-level with the ports c' d² full open. The feed-water enters by the branch A² and passes through the liner C and hollow valve D to the branch A³, leading to the feed-check valve on the boiler. When the water in the boiler rises, it carries the float F with it and causes the valve to move partly around till it closes 80 the ports or causes them to remain sufficiently open to keep the water at a uniform level.

If it should be desired to work with the water at a different level, the valve D is moved along the liner by the screw G, and the ports 85 being diagonal the valve must move farther around to reach the cut-off edge, which means a higher or lower water-level depending upon the direction and amount the valve is moved along the liner.

A rod M is attached to a bridle N, encircling the float-lever E, which leaves the latter free to move in its required directions, but provides for moving the float by hand, so as to test its working or for jerking it for the 95 purpose of expelling any grit or foreign matter that may gather in the valve.

The apparatus may be placed entirely inside the boiler, the regulating-screw being led to the outside.

I claim—

1. An automatic feed-regulator for steam-boilers, comprising a valve having ports for the passage of the feed-water, a float controlling the movements of such valve, and means for shifting the valve independent of the float, whereby the valve is arranged to feed at different water-levels, substantially as set forth.
2. An automatic feed-regulator for boilers, comprising a rotatory valve having ports for the passage of the feed-water, a float for turning the valve about its longitudinal axis, and means for adjusting the valve longitudinally to vary the height of water which will be maintained in the boiler, substantially as set forth.
3. An automatic feed-regulator comprising a casing having inlet and outlet branches, a hollow rotatory valve fitted therein and provided with diagonal ports, a float arranged to move the valve about its longitudinal axis to control the opening and closing of the ports, substantially as set forth.
4. In an automatic feed-regulator, the combination of the casing provided with a valve-seat formed with ports through which the water passes, a rotatory valve mounted therein and provided with diagonal ports, a float arranged to partially rotate the valve by the rise and fall of the water-level, and means for adjusting the rotatory valve longitudinally to

change the position of the ports in the valve relative to those in the valve-casing to cause the water to be maintained at different levels 35 accordingly as the valve is set substantially as set forth.

5. In an automatic feed-regulator, the combination of a rotatory valve provided with ports through which the feed-water passes, a float connected with the valve and arranged to partially rotate the same as the water-level varies, means for adjusting the valve longitudinally, and an antifriction bearing or joint between the valve, and the longitudinal adjusting means, substantially as set forth.

6. The combination of a casing having a cylindrical valve-seat formed with ports, a hollow cylindrical valve mounted therein and provided with diagonal ports d^2 , arranged to 50 register with the ports in the valve-casing, a float connected with the valve and arranged to partially rotate the same as the water-level changes, an adjusting-screw for moving the valve longitudinally, and a ball-bearing connection between the screw and the valve, substantially as set forth.

In testimony whereof I affix my signature in presence of two witnesses.

JAMES H. ROSENTHAL.
